(57)

CLAIM

The ornamental design for an applicator tip as shown and described.

DESCRIPTION

FIG. 1 is a perspective view of an applicator tip showing the new design;

FIG. 2 is a perspective view of the applicator tip shown in an alternate configuration with the applicator tip shown on the nozzle;

FIG. 3 is a side view of the applicator tip of FIG. 1; and, FIG. 4 is a top view thereof.

The broken line showing of the bottle and screw lid in the drawings depict environment and form no part of the claimed design.
